UNITED STATES PATENT OFFICE.

JAMES H. LARRAMORE, OF SHELLTOWN, MARYLAND.

TRAPPER'S TONGS.

1,091,356.

Specification of Letters Patent. Patented Mar. 24, 1914.

Application filed September 19, 1911. Serial No. 350,277.

To all whom it may concern:

Be it known that I, JAMES H. LARRAMORE, a citizen of the United States, residing at Shelltown, in the county of Somerset and State of Maryland, have invented certain new and useful Improvements in Trappers' Tongs; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to a trapper's tongs and has for its object to provide a device for handling traps such as muskrat traps and other fur bearing animal traps which are at times arranged under water and have 20 to be set and removed from the water in such manner that the handling of the traps is attended with ease and comfort and the danger of setting and removing traps under water is entirely eliminated.

25 With this object in view the invention consists in the novel construction of the tongs and in the novel arrangement for operating the jaws thereof, all of which will be first fully described and afterward specifically pointed out in the appended claim.

Referring to the accompanying drawing Figure 1 is a top plan view of a trapper's tongs constructed in accordance with this invention, and Fig. 2 is a side elevation 35 thereof partly in section.

Like numerals of reference indicate the same parts throughout the two figures in which;

1 indicates the tongs which comprise the 40 handle 2, lower jaw 3 and upper pivoted jaw 4. As will appear from the drawing the lower jaw 3 is secured to the handle 2 by means of a socket 5 formed on the jaw 3 into which the handle 2 is placed, the 45 parts being secured together preferably by means of rivets 6. It will be observed that the handle 2 terminates at its lower end in a longitudinally concaved portion in continuation of the corresponding or concaved 50 surface or face of the fixed jaw 3 to co-operate with said jaw in accommodating the movement of the pivoted jaw as the latter is actuated. It will also be observed that, as above intimated, the pivoted jaw is 55 hung in the tubular socket formation 5 of the fixed jaw 3 which thus forms a partial

housing for said pivoted jaw and accordingly guards it against becoming inoperative as would otherwise likely result, especially in breaking the ice with the tongs and 60 submerging the same in the water therebelow.

The upper movable jaw 4 is pivoted to the lower jaw 3 at the point 7, and a spring 8 is applied at this point having one end 65 bearing against the lower jaw 3 and the other end in engagement with the upper jaw 4 in such manner as to hold the jaws in a closed position as illustrated in full lines in Fig. 2.

70 The pivoted upper jaw 4 has an opening therethrough into which is received an up-standing plate-like stud 4^a having an aperture 4^b which receives and forms a bearing for the pivot 7 of said upper jaw, the end 75 portions of said pivot being received by the jaw, the spring 8 being coiled around said pivot within said aperture 4^b of the jaw. By thus locating the pivot of the upper pivoted jaw and the spring delivering pres- 80 sure upon said jaw these several parts, namely, the pivot, its supporting stud and the jaw-engaging spring, are all suitably housed or guarded as against liability of contact with any obstruction and accord- 85 ingly their impairment or displacement as would be very likely to be the case in thrusting the device through and in breaking the ice with the jaws as would be required in disposing the jaws below the ice as in plac- 90 ing the jaws thereunder.

Arranged on the handle 2 is the operating wire 9 which is connected at one end to the upper movable jaw 4 at the point 10 and having its other end connected to a 95 thumb lever 11, said thumb lever 11 being pivoted at 12 in the handle 2 as clearly shown in Fig. 2. A plurality of staples 13 are arranged on the handle 2 through which the operating wire 9 passes in such manner 100 as to protect and guide said wire and prevent the same from buckling or bending.

Having thus described the several parts of this invention its operation is as follows: The handle of the tongs is of a sufficient 105 length to enable a trap to be engaged within the jaws so as to conveniently place the trap into a lead or other convenient place for the trapping of animals in such manner that the trap can be placed in proper 110 position without submerging the hand, the tongs being of such a character that the

jaws can be used for breaking ice whenever the trap is carried under the ice and the trap can be quickly and conveniently removed by means of the tongs without danger to the hand of the operator and without immersing the same in the water.

It will be seen by reference to Fig. 2 that the co-acting surfaces of the jaws 3 and 4 are flat in cross section and curved in longitudinal section in order to more rigidly grip the trap and hold the same.

Having thus described the invention it is clearly apparent that changes may be made in the construction and arrangement of the parts without departing from the limit and scope of this invention, and I consider myself clearly entitled to all such modifications as fall within the appended claim.

20 What I claim as new and desire to secure by Letters Patent of the United States, is:—

Tongs of the type described, including a handle, a fixed jaw secured to one end of said handle and having a concaved gripping or engaging surface or face, said con-

cavity having outstanding lateral walls intermediate the ends of the jaw, said jaw having near its midlength an upstanding stud, a movable jaw having an inner convex surface conforming in outline to the concavity of the fixed jaw, said movable jaw having an aperture therethrough about at its midlength receiving said stud, a pivoting pin or pintle effecting pivotal connection between said movable jaw and said stud, a lever fulcrumed in said handle, a flexible connection between said movable jaw and said lever, said flexible connection having one end secured to said movable or pivoted jaw inwardly of the pivotal point of the jaw, and a spring centrally connected to the pivot of the movable jaw, said spring delivering its pressure upon the movable jaw to initially retain the jaws closed.

In testimony whereof, I affix my signature, in presence of two witnesses.

JAMES H. LARRAMORE.
